UNITED STATES PATENT OFFICE.

GARTH G. GILPIN, OF RIVERSIDE, ILLINOIS, ASSIGNOR TO P. H. MURPHY COMPANY, OF NEW KENSINGTON, PENNSYLVANIA, A CORPORATION OF PENNSYLVANIA.

METAL ROOF FOR FREIGHT CARS.

Application filed February 3, 1922. Serial No. 533,840.

This invention relates to improvements in freight cars and more particularly to metal roofs for freight cars.

Roofs of metal are replacing the wooden or wood and metal roofs for freight cars and it is an object of this invention to provide a roof of metal plates or sheets so constructed as to be self supporting, without the necessity of carlines, and of sufficient strength to support the load to which car roofs are normally subjected. Another object of this invention is to so construct a metal roof that the condensation on the inner side of the roof sheets caused by the temperature being unequal on opposite sides of the sheets will be reduced to a minimum by ventilating the roof in such a manner that the temperature will be nearly equal on both sides.

20. While the preferred form of this invention is illustrated upon the accompanying sheet of drawing, yet it is to be understood that minor detail changes may be made without departing from the scope thereof.

25. In the drawings:

Fig. 1 is a top plan view of a portion of a freight car illustrating this improved roof.

30. Fig. 2 is a view in section taken on the line 2—2 of Fig. 1.

Fig. 3 is an enlarged detail view in section taken on the line 3—3 of Fig. 2, with parts shown in perspective.

35. Figs. 4 and 5 are similar views taken on the lines 4—4 and 5—5 respectively of Fig. 2.

Fig. 6 is a view similar to Fig. 3 illustrating a modified form of ventilated opening.

40. In the embodiment of this invention, as illustrated, the roof is composed of a number of metal sheets 1 which overlap at one edge the adjacent sheet with the sheets extending continuously across the car having their ends resting upon and secured to the side plates. The side plates 2 are illustrated as angle irons and the roof sheets are shown of a conventional form in that they are provided with a flat portion 3 at the ridge or longitudinal center which is higher than the side plates so that the sheets slope downward on each side thereof.

45. The roof sheets are preferably pressed from similar rectangular plates of metal with parallel ribs pressed from the body

thereof near the opposite edges. The bends in all of the plates are alike for the slope from the ridge to the sides so that before the ribs are pressed the edge of one sheet would overlap the adjacent edge of the other in 60 perfect contact throughout. The ribs 4 and 5 near the opposite edges of each sheet are pressed from opposite sides of the sheet. The ribs are preferably U-shaped and of the same width. The ribs 4 near one edge are pressed inward from the top of the sheet and decrease in depth from the flattened portion at the ridge until they merge into the plane of the sheet just before the sheet rests on the side plates and this edge is naturally overlapped by the adjacent sheet. The ribs 5 along the opposite side of this sheet are pressed upward from the underside an equal height at each end and decrease in height towards the ridge until they 70 merge into the plane of the sheet about half way from the side plate and the flattened portion at the ridge.

75. As the ribs are pressed from the body of the sheets adjacent the transverse edges there will be a flange on the outer side of each rib in the plane of the sheet, and as the sheet is formed from the rectangular plate and the ribs are parallel to each other and to the original edges of the plate, the flanges on the outer edges will vary in width in accordance with the depth or height of the ribs 4 and 5 and therefore the sheet will have the overlapping edge flanges 80 narrowing in width towards the ends and the overlapped edge flanges 7 widening towards the edges, as shown in full and dotted lines of Fig. 1.

85. The ends 8 of the sheets preferably extend beyond the side plates and are bent down 95 therefrom, as shown, to form a weather proof joint. The tops of the upward pressed ribs are also bent down to the side of the car to form a baffle 9 but allow the passage of air therethrough. When the sheets are 100 placed on the car with the upstanding ribs of one overlapping the down pressed rib of the adjacent sheet the two ribs form a continuous passage 10 from one side of the car to the other between the sheets and the sheets are secured to each other by a line of rivets on each side of the respective ribs which pass through the sheet and the flange extending beyond the ribs on the other sheet, 105 as shown in Fig. 1.

To equalize the temperature throughout the underside of the roof without weakening the roof structure a plurality of vertical apertures are provided in the side walls of 5 the ribs and preferably in the wall furthest away from the body of the sheet. These 10 ventilating apertures may be circular openings 11 punched in the side walls, as shown in Figs. 1 and 3, or may be formed by slitting 15 the metal of the rib parallel to the body of the sheet and then pressing the metal above the slit inward, as shown in Fig. 6, which latter opening 12 does not detract as much from the strength of the wall of the 15 rib.

In practice the line or plane along the base of the U in the direction of its greatest dimension will lie parallel to the same line or plane of the adjacent rib on the opposite 20 side of the sheet and since, when the sheets are overlapped and secured together, the adjacent ribs lie over each other the air passage 10 from the ends will be approximately constant until past the inner end of the 25 upper ribs and then increase in size in accordance with the depth of the under rib.

The sweating of the metal roof sheets is caused by the atmosphere in the car being of higher or lower temperature than the 30 sheets and the condensation drops down upon the lading. By this construction an air passage is formed at the adjacent edges of the sheets from side to side of the car allowing free circulation in the outside atmosphere and the ventilating openings in the 35 walls of this passage allow circulation of the atmosphere between the interior and exterior of the car through these passages and thereby equalizes the temperature nearest the 40 roof sheets on each side so that sweating will be reduced to a minimum. The ribs of one sheet being a continuation of the ribs of the adjacent sheet take the place of carlines and the flanges extending outward from each rib 45 provide means for securing the bodies of the two adjacent sheets to each other on each side of the ribs and thereby not only insuring registration of the two ribs of the opposite sheets at all times, but also adds to the 50 strength and rigidity of the roof structure as a whole.

What I claim is:

1. A roof sheet formed from a rectangular blank of metal having parallel ribs therein 55 adjacent the opposite edges extending from opposite sides of the sheet, the ribs adjacent one edge extending from the ends of the sheet and merging into the plane of the sheet intermediate the ends and ridge or center line, and having a flange extending exteriorly of the ribs lying in the plane of the sheet.

2. A metal roof formed from a rectangular blank of metal having parallel ribs 60 therein adjacent the opposite edges extend-

ing from opposite surfaces of the sheet, the ribs adjacent one edge of the sheet extending from the ridge or center line and merging into the plane of the sheet adjacent the ends of the sheet, and having a flange extending 70 exteriorly of the ribs lying in the plane of the sheet.

3. A roof sheet formed from a rectangular blank of metal having parallel ribs therein adjacent the opposite edges extending from 75 opposite sides of the sheet, the ribs adjacent one edge extending from the ends of the sheet and merging into the plane of the sheet intermediate the ends and ridge or center line, the ribs adjacent the opposite edge of 80 the sheet extending from the opposite side of the sheet in one direction and from the ridge or center line and merging into the plane of the sheet adjacent the ends thereof in the other direction, each rib having a 85 flange extending exteriorly thereof lying in the plane of the sheet.

4. A roof sheet formed from a rectangular blank of metal having parallel ribs therein adjacent the opposite edges extending from 90 opposite sides of the sheet, the ribs adjacent one edge extending from the ends of the sheet and merging into the plane of the sheet intermediate the ends and ridge or center line, and having a flange extending exteriorly 95 of the ribs lying in the plane of the sheet, said flanges decreasing in width in proportion to the amount of metal in the rib pressed away from the sheet.

5. A roof sheet formed from a rectangular blank of metal having parallel ribs therein adjacent the opposite edges extending from 100 opposite sides of the sheet, the ribs adjacent one edge extending from the ends of the sheet and merging into the plane of the sheet 105 intermediate the ends and ridge or center line, the ribs adjacent the opposite edge of the sheet extending from the opposite side of the sheet in one direction and from the ridge or center line and merging into the plane of the sheet adjacent the ends thereof 110 in the other direction, the bottom of the rib or ribs on one side of the sheet lying in planes parallel to the plane of the bottom of the rib or ribs on the opposite side of the sheet and adjacent the opposite edges of the sheet.

6. In a metal car roof, a plurality of roof sheets extending from side to side, each sheet having one edge overlapping the edge of the adjacent sheet and parallel ribs in each sheet extending from opposite sides of the sheet, and merging into the plane of their respective sheets, the ribs on the upper side of the overlap increasing in height towards and open at the car sides and the ribs on the underside decreasing in height from the center to the car sides.

7. In a metal car roof, a plurality of roof sheets extending from side to side, each sheet 130

having one edge overlapping the edge of the adjacent sheet and parallel ribs in each sheet extending from opposite sides of the sheet, and merging into the plane of their respective sheets, the ribs on the upper side of the overlap increasing in height towards the car sides and the ribs on the underside decreasing in height from the center to the car sides. 5

10 provided with apertures opening into the interior of the car.

8. In a metal car roof, a plurality of roof sheets extending from side to side, each sheet having one edge overlapping the edge of the adjacent sheet and parallel ribs in each sheet extending from opposite sides of the sheet, and merging into the plane of their respective sheets, the ribs on the upper side of the overlap increasing in height towards the car sides and the ribs on the underside decreasing in height from the center to the car sides, 15 a side of the under rib provided with apertures opening into the interior of the car.

9. In a metal car roof, a plurality of roof sheets extending from side to side, each sheet having one edge overlapping the edge of the adjacent sheet and parallel ribs in each sheet extending from opposite sides of the sheet, and merging into the plane of their respective sheets, the ribs on the upper side of the overlap increasing in height towards the car sides and the ribs on the underside decreasing in height from the center to the car sides. 20

9. In a metal car roof, a plurality of roof sheets extending from side to side, each sheet having one edge overlapping the edge of the adjacent sheet and parallel ribs in each sheet extending from opposite sides of the sheet, and merging into the plane of their respective sheets, the ribs on the upper side of the overlap increasing in height towards the car sides and the ribs on the underside decreasing in height from the center to the car sides, 25 a side of the under rib provided with apertures opening into the interior of the car. 30
